(57) **CLAIM**

The ornamental design for an environmental sampling device as shown and described.

DESCRIPTION

FIG. 1 is a front and top perspective view of an environmental sampling device in accordance with the present

design, the environmental sampling device including a top section snap-fit into engagement with a bottom section; FIG. 2 is a front and bottom perspective view of the environmental sampling device of FIG. 1;

FIG. 3 is a top plan view of the environmental sampling device of FIG. 1;

FIG. 4 is a front elevational view of the environmental sampling device of FIG. 1;

FIG. 5 is a left side elevational view of the environmental sampling device of FIG. 1, with the right side view being a mirror image thereof;

FIG. 6 is a front and top perspective view of just the top section of the environmental sampling device of FIG. 1;

FIG. 7 is a front and bottom perspective view of just the top section of the environmental sampling device of FIG. 1;

FIG. 8 is a top plan view of just the top section of the environmental sampling device of FIG. 1;

FIG. 9 is a front elevational view of just the top section of the environmental sampling device of FIG. 1;

FIG. 10 is a left side elevational view of just the top section of the environmental sampling device of FIG. 1, with the right side view being a mirror image thereof;

FIG. 11 is a front and top perspective view of just the bottom section of the environmental sampling device of FIG. 1;

FIG. 12 is a front and bottom perspective view of just the bottom section of the environmental sampling device of FIG. 1;

FIG. 13 is a top plan view of just the bottom section of the environmental sampling device of FIG. 1;

FIG. 14 is a front elevational view of just the bottom section of the environmental sampling device of FIG. 1; and,

FIG. 15 is a left side elevational view of just the bottom section of the environmental sampling device of FIG. 1, with the right side view being a mirror image thereof.

The broken lines in the drawings show portions of the environmental sampling device that form no part of the claimed design.
